UNITED STATES PATENT OFFICE.

THOMAS ALLATT AND LOUIS A. KERWIN, OF PORTLAND, OREGON.

MAIL RECEIVING AND DELIVERING APPARATUS.

No. 893,967.

Specification of Letters Patent.

Patented July 21, 1908.

Application filed March 30, 1908. Serial No. 424,098.

To all whom it may concern:

Be it known that we, THOMAS ALLATT and LOUIS A. KERWIN, citizens of the United States, residing at Portland, in the county of Multnomah and State of Oregon, have invented certain new and useful Improvements in Mail Receiving and Delivering Apparatus, of which the following is a specification, reference being had therein to the accompanying drawing.

This invention relates to a delivering apparatus or mechanism, and has for its object the provision of means for facilitating the delivery of, preferably, a mail bag or receptacle from a moving train to a receiving device carried by a stationary support.

Another object of the invention is the provision of means for receiving an object from a moving train, and after the object is received, the same may be carried a short distance, the momentum being quickly overcome, and the object being held in a stationary position.

With these and other objects in view, the invention consists of certain novel constructions, combinations, and arrangements of parts, as will be hereinafter fully described and claimed.

In the drawings: Figure 1 is a view in elevation of an apparatus constructed in accordance with the present invention. Fig. 2 is a view in front elevation of the receiving device. Fig. 3 is an enlarged, fragmentary view of the structure depicted in Fig. 1. Fig. 4 is an enlarged view of the bag-engaging and supporting device depicted in Fig. 2. Fig. 5 is a top plan view of the bracket carried by the car. Fig. 6 is a transverse, sectional view taken on line 6, 6, Fig. 5. Fig. 7 is a view, in elevation, of the ring and hook. Fig. 8 is a top plan view of the device depicted in Fig. 4, and Fig. 9 is a horizontal, sectional view thereof, showing the eye-beam positioned therein and in section. Fig. 10 is a transverse, vertical, sectional view of the device depicted in Fig. 9. Fig. 11 is an end view of one of the end-sections of the device depicted in Fig. 4. Fig. 12 is a fragmentary view of one of the brackets carrying the eye-beam and the guide-member for the bell-crank lever, and Fig. 13 is a view, in transverse section, of a portion of the structure depicted in Fig. 12, showing the guide member in end elevation. Fig. 14 is an end view of the bell-crank lever. Fig. 15 is an en-

larged view, looking at the end of the receiving and holding-device.

Referring to the drawings, 1 designates, preferably, a car carrying brackets 2 provided with vertically-extending pins 3. The pins 3 extend through vertical, apertured portions of the hinged or pivoted bracket 4. The horizontal bracket is intended to swing around into the car, so that the door may be closed when mail is not being delivered or received. The bracket 4 is provided, at its upper, outer, edge with a ring-supporting body 5. The body 5 is provided with a vertical recess or cut-out portion 6, and with annularly-grooved portions 7 for facilitating the seating of a ring 8 upon the lugs 9. The lugs 9 are very strong, and are provided upon their upper face with a beveled portion or socket 10, Fig. 6, so that the ring 8 can be easily seated and normally held upon the bracket, prior to displacement as hereinafter described.

The ring 8 is provided with a pivotally-mounted hook 11, which hook is provided with prongs 12 that are adapted to receive a mail bag 13, Fig. 1, or any other object, to be received off of the bracket 4. The weight of the bag 13, carried by the prongs or hooks 12, will hold the ring in a seated position, but owing to the curved structure of the holding lugs (which lugs only engage the lower portion of the ring 8) the bag and the ring can be easily lifted or removed off of the bracket by said ring engaging the pivotally-mounted hook member 14 of the receiving device, as hereinafter described.

The receiving-device comprises, preferably, a pair of uprights or standards 15, which are, preferably, connected by a horizontal beam 16 for bracing the same. Brackets 17 are secured upon the same sides of the uprights or standards 15, and in these brackets is rotatably mounted a supporting-rod or shaft 18. Arms 19 are mounted upon the rod or shaft 18, contiguous to the bracket 17, and each arm 19 is fixed against independent rotary movement with respect to the rod 18 by any suitable fastening means, as for instance set-screw 20. The arms 19 are provided with rearwardly-extending extensions 21 carrying weights 22, for performing the function of a counterbalance.

To the outer ends of the arms 19, there is fixedly secured, preferably, an eye-beam or track 23.

Slidably mounted upon eye-beam 23 is a bag-engaging and supporting device, which comprises a frame composed, preferably, of end-sections 24 and a central section 25. The end-sections and the central-section 24 and 25, respectively, are fixedly secured together by horizontal, upper and lower bars or pieces 26 and 27, which are suitably secured to the sections. A front guide-member 28 is secured within the frame, and a rear guide or brake-member 29 is also secured within the frame. The front guide-member 28 is provided, at its end, with right-angularly-disposed portions 30 and the brake-member 29 is provided, at its ends, with right-angularly disposed portions 31. The angle-portions 30 and 31 of the members 28 and 29 are positioned in opposite directions and engage opposite vertical edges of the end-sections 24 of the frame, Fig. 9. The angularly-disposed ends 30 are provided with elongated openings or apertures 32, Fig. 11, in which is mounted a slidable set-bar 33; the bar 33 may be projected a considerable distance beyond either end of the frame, for the purpose hereinafter specified. Near the center of the bar 33 is secured a horizontal-extending pin or lug 34, which slides in an elongated slot 35 formed in a vertically-extending extension 36, which is fixed to shaft 37 carrying the hook-member 14. The hook-member 14 is also fixed against independent rotary movement upon shaft 37, as well as the extension of arm 36. By projecting the bar 37 in the direction shown by the arm in Fig. 4, the hook-member 14 will be swung to the position shown by dotted lines 38, Fig. 4, for engaging a ring 8, Fig. 1. The hook-member 14 is provided with hooks 14^a at its ends, so that a ring may be engaged on a train moving in either direction. When the receiving-device, Figs. 2 and 4, is set, the same is moved to the end of the eye-beam nearest to the on-coming train, and the set-bar 33 is projected, as shown in Fig. 2, for permitting the holding-bracket 39, pivotally mounted upon bracket 40, to engage the set-bar 33. The advantage of this peculiar structure is that the bag-receiving device is only held in an operative position when it is set, and as soon as the device is engaged by the ring and the same starts to slide along the eye-beam 23, the set-bar 33 will be automatically disengaged from the hook, causing the receiving-device to be automatically swung down away from the moving train. The device is only set when the bag-engaging and holding device, Fig. 4, is at one end of the eye-beam, Fig. 3, and, consequently, it will be noted that the device is provided with means for instantaneously causing the rod 18 to be swung and removing the device from near the moving object or train.

To overcome the momentum of the ring 8 and the bag or object carried thereby, we

have provided a brake upon the bag-supporting and receiving device, which comprises said brake-bar or member 29 and an inwardly-bowed spring 41, Fig. 9, which spring constitutes a yielding or presser member normally exerting inward pressure upon the bar 29 for causing the same to grip or bear against the body of the eye-beam 23. Greater pressure can be exerted upon the brake-member or shoe 29 by threading inward the set-screws 42, as will be obvious upon considering Fig. 9. The spring 41 is provided with a fixed, horizontal extension 43, which extends rearwardly, and is positioned between the bifurcated portion 44 of the bell-crank lever 45. A suitable fastening member, as for instance, 46, extends transversely through the extension 43, and through elongated openings or apertures 47 formed in the bifurcated portion of lever 45, Fig. 14, thereby permitting the lever to be swung upon its pivot 48 carried by an extension 49 formed on the central section 25. It will be obvious that upon swinging the outer end of lever 45 downward, the brake-member 29 will be partly or entirely removed. Therefore, we have provided means for controlling the pressure upon the eye-beam for partly or entirely removing the brake, if desired. It is desirable to permit the bag-engaging and supporting device to move freely when the bag is delivered thereto, through the medium of the ring 8, and consequently, we have provided a guide-bar or member 50, at each end of the eye-beam, Figs. 10, 12, and 13, which is bent near its end, as at 51, so that the lever will be held downward at an angle to a horizontal plane, when the device is set, Fig. 2, but as soon as it has traveled a few inches on the eye-beam 23, the upwardly or outwardly-extending central portion of the guide-member 50 will permit the lever to swing upward and thereby gradually allow the brake to be applied to the eye-beam for slowing down or overcoming the momentum or sliding movement of the bag-receiving and supporting means carried by the eye-beam. Consequently, it will be understood that we have provided automatic means for permitting the set-device to be slowed down after it receives its load, and, furthermore, load-receiving and holding means slidably mounted upon a support, and brake-means co-operating with said load-receiving and holding means for gradually retarding and stopping sliding movement which will prevent any impact or sudden jar, and thereby practically eliminating the possibility of injuring the device, which is of great importance; it is to be noted that we have provided a very practical and efficient structure, which is positive in operation and comparatively inexpensive to construct or manufacture, for the delivery of mail, despatches, or any other object suitably supported by a moving train.

While we have described in the specification the member 8 as a "ring," we desire to be understood that we use this in a generic sense, for any suitable form may be employed 5 other than a ring or circular-shaped member, and, therefore, we use the word ring in the sense of an engaging or bag-supporting member, as and for the purpose above described.

In Fig. 15, I have shown an enlarged view 10 of the holding and receiving device, in which a notch 33^a is formed at each end of bar 33. The object of the notch is to bring the face of set-bar 33, that comes in contact with the end of holding bracket or arm 39 square 15 with the line of resistance. The overhanging-piece 39^a will rest on the top edge of said bar 33, and thus it will drop into position, instead of having to be set carefully by hand.

What we claim is:

20 1. In an apparatus of the class described, the combination with a support, of a bracket carried by said support, said bracket provided with supporting-lugs at one side and with a cut-out portion contiguous to said 25 lugs, said lugs and cut-out portions adapted to receive bag supporting means, and means for removing said object-supporting means from said lugs.

2. In an apparatus of the class described, 30 the combination with a support, of a bracket carried by said support, said bracket provided with a body portion, said body portion provided with a vertical cut-out portion, and with lugs at opposite sides of said cut-out 35 portion, said lugs provided with faces adapted to receive a bag-holding member, said bag-holding member provided with means for engaging a bag, said engaging means positioned in the cut-out portion of said bracket, and 40 means for removing said bag-holding member from said bracket.

3. In an apparatus of the class described, 45 the combination with a support, of a bracket carried by said support, said bracket provided at one side with bag-supporting means and with a cut-out portion, said bag-holding means comprising a body and bag-engaging means, said engaging means positioned in the 50 cut-out portions of said bracket, and means for removing said bag-holding means from said bracket.

4. In an apparatus of the class described, 55 the combination with a bracket, of a ring-engaging one side of said bracket, means detachably securing the ring upon the side of said bracket, said bracket provided with a cut-out portion, said ring provided with a hook positioned in said cut-out portion, and means for moving said ring bodily away 60 from one side of said bracket.

5. In an apparatus of the class described, 65 the combination with a support, of a movably-mounted track carried by said support, bag-receiving and holding means slidably mounted upon said track, and a brake car-

ried by said bag-receiving means and adapted to engage the track for limiting movement of said receiving means.

6. In an apparatus of the class described, 70 the combination with a support, of a movably-mounted track carried by said support, a bag-receiving device slidably mounted upon said track, said bag-receiving device provided with a set-bar and with a hook-member, means connecting said hook-member 75 and said set-bar, whereby when said set-bar projects beyond one end of said bag-receiving device, said hook-member will be positioned for receiving a load, and means for engaging said set-bar for holding the device in a set 80 position until the load is delivered to said bag-receiving device.

7. In an apparatus of the class described, 85 the combination with a support, of a rod pivotally mounted upon said support, arms fixedly secured to said rod, an eye-beam fixedly secured to said arms, and bag-receiving means slidably mounted upon said eye-beam and provided with means engaging said eye-beam for retarding and stopping movement 90 of said bag-receiving means thereon.

8. In an apparatus of the class described, 95 the combination with a support, of arms pivotally mounted upon said support, said arms provided with extensions, weights slidably mounted upon said extensions, a track secured to said arms, and bag-receiving means carried by said track and provided with a brake for normally retarding sliding movement thereof upon the track. 100

9. In an apparatus of the class described, 105 the combination with a track, of bag-receiving means slidably mounted upon said track, said bag-receiving means provided with a brake engaging said track, and means for preventing said brake from retarding the movement of said bag-receiving means at the time an object or bag is delivered thereto.

10. In an apparatus of the class described, 110 the combination with a support, of a track pivotally mounted upon said support, means for holding said track in a set position, and bag-receiving means engaging said holding means when in a set position and capable of being automatically disengaged from said 115 holding-means when a bag or load is delivered thereto.

11. In an apparatus of the class described, 120 the combination with a support, of arms pivotally mounted upon said support, a track secured, at its ends, to said arms, and means traveling upon said track for receiving a load from a moving object.

12. In an apparatus of the class described, 125 the combination with a support, of arms pivotally mounted upon said support, a track secured at its ends to said arms, and means traveling upon said track between the arms for receiving a load from a moving object, said receiving-means provided with means 130

for limiting and entirely stopping the travel of said receiving means upon said track.

13. In an apparatus of the class described, the combination with a support, a track carried by said support, of a bag-receiving device carried by said track, said bag-receiving device comprising a frame, a hook-member pivotally mounted upon said frame, brake means carried by said frame, and means for adjusting said brake-means upon said frame.

14. In an apparatus of the class described, the combination with a track, of a bag-receiving device slidably mounted upon said track, said bag-receiving device provided with a brake, furnished with means for varying the pressure of the brake upon the track during movement of the bag-receiving device.

15. In an apparatus of the class described, the combination with a track, of a movable bag-receiving device carried by said track, said bag-receiving device provided with a shaft, bag-receiving means fixedly secured to said shaft, an extension fixedly secured to said shaft, a set-bar carried by said frame and provided with means engaging said extension, whereby when said set-bar is projected beyond one end of the frame, said bag-receiving means will be set for receiving a load.

16. In an apparatus of the class described, the combination with a track, of a slidably bag-receiving device carried by said track, said device provided with a set-bar, and a bag-receiving hook or member, and means connecting said set-bar to said hook, whereby when said set-bar is adjusted upon the device, the hook will be positioned for receiving a load.

17. In an apparatus of the class described, the combination with a track, of a bag-receiving device slidably mounted upon said track, said device provided with a brake engaging said track, lever means connected to said brake, and means coöperating with said lever means for placing the brake in an inoperative position, when the device is set for receiving a load and adapted to permit the brake to be applied subsequent to the delivery of the load to the device.

18. In an apparatus of the class described, the combination with a track, of a bag-receiving device slidably mounted upon said track, and clamping means carried by said device and adapted to engage said track for limiting or stopping movement of said device upon said track.

19. In an apparatus of the class described, the combination with a track, of a bag-receiving device slidably mounted upon said track, means carried by said device for retarding sliding movement thereof upon said track, and means for permitting the device to have a free sliding movement at the time a load is delivered thereto.

20. In an apparatus of the class described, the combination with a track, of a slidable

bag-receiving device mounted upon said track, and a yieldable brake carried by said device and adapted to engage the track for gradually overcoming the momentum of the device subsequent to the delivery of a load thereto.

21. In an apparatus of the class described, the combination with a support, a track carried by said support, of a movable bag-receiving device provided with a bar, mounted upon said bracket, said bar provided with a beveled or notched portion, a supporting arm or bracket movably mounted upon said support and provided with an end or shoulder adapted to engage the beveled or notched portion of the bar, and said bracket provided with an extension adapted to overhang a portion of the bar and limit movement of the bracket in one direction upon the bar.

22. In an apparatus of the class described, the combination with a track, of a bag-receiving device slidably mounted upon said track, and said bag-receiving device provided with clamping means adapted to engage opposite portions of the track for retarding the sliding movement of the bag-receiving device.

23. In an apparatus of the class described, the combination with a track, of a load-receiving device slidably mounted upon said track, said load-receiving device provided with a brake slidably engaging the track, and said brake adapted to clamp the track for retarding and eventually stopping the sliding movement of the load-receiving device.

24. In an apparatus of the class described, the combination with a support, of arms pivotally mounted upon said support, a track secured to said arms, a load-receiving device movably mounted upon said track, and provided with means for clamping the track for limiting movement of said load-receiving device.

25. In an apparatus of the class described, the combination with a support, of a movable track carried by said support, a load-receiving device adapted to travel upon said track, said load-receiving device provided with an extension, means carried by said support and adapted to engage the extension for holding the track and load-receiving device in a set position, and said extension being adapted to disengage said holding means when a load is delivered to said load-receiving device for releasing the track and receiving-device and permitting the track to fall to an inoperative position.

26. In an apparatus of the class described, the combination with a support, of a track carried by said support, a load-receiving device carried by said track and provided with brake-means for limiting movement of the load-receiving device upon said track, and means carried by said track for varying the pressure of said brake upon the track rela-

- tive to the position of the load-receiving device upon the track.
27. In an apparatus of the class described, the combination with a support, a track carried by said support, of a traveling load-receiving device carried by said track, said device provided with a swinging hook, and said device provided with means for holding said hook in one of a number of positions for receiving a load.
28. In an apparatus of the class described, the combination with a support, of a bracket pivotally mounted upon said support, said bracket provided with a semi-circular body portion at one end and a series of lugs formed upon one side of said bracket and contiguous to said semi-circular body portion, and each lug provided upon its upper face with a ring-receiving socket or pocket, and a bag-supporting ring adapted to be seated in all of the sockets of the lugs.
29. In an apparatus of the class described, the combination with a support, of a track carried by said support, said track provided with a sliding load-receiving device, said load-receiving device provided with a set-bar and a hook coöperating with said set-bar, said set-bar adapted to be projected beyond one end, and means for engaging the projected end for holding the hook in a set position upon the device.
30. In an apparatus of the class described, the combination with a support, of a track carried by said support, a load-receiving device slidably mounted upon said track, said load-receiving device provided with a clamp, a bifurcated lever carried by said device, means positioned in the bifurcated portion of said lever and secured to said clamp, whereby when the lever is swung the position of the clamp is varied relative to the track.
31. In an apparatus of the class described, the combination with a support, a track car-
- ried by said support, of load-receiving means movably mounted upon said track, said load-receiving means provided with brake-means, said load-receiving means provided with manually-operated lever means connecting said lever to said brake means, whereby the pressure of the brake upon the track may be varied.
32. In an apparatus of the class described, the combination with a support, of a bracket carried by said support, load-receiving means movably mounted upon said bracket, said load-receiving means provided with brake-means, means connecting said brake means to said lever means, and means for engaging said lever means for holding the brake-means in an inoperative position at the time the load is delivered to said load-receiving means.
33. In an apparatus of the class described, the combination with a support, of a load-receiving device carried by said support, said load-receiving device provided with a slidable member having an extension or projection, a pivotally-mounted load-receiving member carried by said device and having said extension projecting therethrough, whereby when said pivotally mounted member is adjusted, said load-receiving member will be moved to a set position upon said device.
34. In an apparatus of the class described, the combination with a track, of a load-receiving device slidably-mounted upon said track, a hook pivotally mounted upon said device, and means for holding said hook in a set position when said device is supported near one end of said track.

In testimony whereof we hereunto affix our signatures in presence of two witnesses.

THOMAS ALLATT.
LOUIS A. KERWIN.
